[57] **CLAIM**

The ornamental design for a pizza pan, as shown and
described.

DESCRIPTION

FIG. 1 is a top plan view of a pizza pan, showing my new
design;

FIG. 2 is a rear elevational view thereof;

FIG. 3 is a front elevational view thereof;

FIG. 4 is a side elevational view thereof, the opposite side
being a mirror image of that shown; and,

FIG. 5 is a bottom plan view thereof.
